(51) **LOC (12) Cl.** ..... **28-99****CLAIM**(52) **U.S. Cl.**

The ornamental design for a fragrance diffuser element, as shown and described.

USPC ..... **D23/366**(58) **Field of Classification Search****DESCRIPTION**

USPC D23/314, 325, 333-336, 355-367, D23/386-388

FIG. 1 shows a perspective view of a design for a fragrance diffuser element.

CPC . A61L 9/03; A61L 9/012; A61L 9/015; A61L 9/037

FIG. 2 shows a first side view of the design.

See application file for complete search history.

FIG. 3 shows a second side view of the design, rotated a 1/4-turn relative to the first side view.

(56) **References Cited**

FIG. 4 shows a top view of the design.

U.S. PATENT DOCUMENTS

FIG. 5 shows a bottom view of the design.
